UNITED STATES PATENT OFFICE

JOHN P. WILLIAMS, OF FRESNO, CALIFORNIA

DIRECTION SIGNAL FOR MOTOR VEHICLES

Application filed February 18, 1929. Serial No. 340,798.

This invention relates to direction signals for motor vehicles, especially closed cars, one object of my invention being to provide a device of this character which may be easily attached to a vehicle so that the signal may be readily seen both from the front and rear of the same, and which avoids the need of giving hand signals.

Further objects are to provide a signal of such a nature as will be effective both by night and by day, which is neat and ornamental in appearance, and in which the operating mechanism is arranged so that a positive signal may be accurately and quickly given, and which when given leaves both hands of the driver free for the proper manipulation of the vehicle.

A further object of the invention is to produce a simple and inexpensive device and yet one which will be exceedingly effective for the purpose for which it is designed.

These objects I accomplish by means of such structure and relative arrangement of parts as will fully appear by a perusal of the following specification and claim. In the drawings similar characters of reference indicate corresponding parts in the several views:

Fig. 1 is a rear view of my improved signal device as connected to the front body post of a motor vehicle.

Fig. 2 is a cross section of the signal arm.

Fig. 3 is a longitudinal section of the arm.

Fig. 4 is a longitudinal section of the switch box.

Fig. 5 is a cross section of the box taken on the line 5—5 of Fig. 4.

Referring now more particularly to the characters of reference on the drawings, the numeral 1 denotes a bracket to be applied against the outside of the left front body post 2 and on which the signal arm is mounted, and 3 is the switch box cover and bracket unit combined, adapted to be applied against the inner face of said post.

The outer and inner brackets are rigidly connected together and clamped against the post by a pair of vertically spaced tubular bolts 4 projecting through the post.

50 The signal arm comprises a cylindrical

glass tube 5 closed at its outer end and covered by a metal sheath 6 of similar shape but somewhat longer and having longitudinally and horizontally opposed windows 7 in its front and back sides. A socket 8 to removably receive the base of a standard light bulb 9 removably fits in the inner end of the sheath and bears at its outer end against a resilient washer 10 engaged with the inner end of the glass tube. This socket member is provided with a standard contact pin structure 11 with which the current conducting wire 12 is adapted to be operatively connected in the customary manner. A metal cap 13 is arranged to fit over the inner end of the sheath and to be secured thereto by the ordinary bayonet lock arrangement indicated at 14. When the cap is thus mounted a flange 15 on the cap bears against the inner end of said socket 8 and presses the same against the washer 10; also acting to press the outer end of the tube against a resilient pad 16 mounted in the outer end of the sheath between said sheath and tube. In this manner all parts of the socket are readily detachable but when assembled are prevented from any loose play relative to each other.

The end cap is provided with an ear 17 to engage the bracket 1 and is pivotally connected thereto by a horizontal pin 18. A short arm 13a projects upwardly from the cap and serves as the connection for one end of a pull wire 19 which projects through the upper bolt 4. At its inner end this wire is connected to the upper end of an arm 20 which projects upwardly from and is fixed on the forward end of a horizontal shaft 21 which extends lengthwise of the vehicle. This shaft is mounted in the hollow switch box structure which is made of insulation material and is mounted in and supported by the metal cover 3. The shaft projects through the rear face of this cover and is provided with a turning knob 23.

The shaft is also of insulation material and on the interior of the box is provided with a circular metal band 24 whose ends are separated, the plane of separation being on top of the shaft when the latter is turned to move the signal arm to a neutral position.

Secured at one end in the box in vertically opposed and insulated relation to each other are spring contact strips 25, one of which engages the top of the shaft between the band 5 or the adjacent portion of the band, while the other constantly engages said band on the bottom of the shaft. One strip is connected to the wire 12 and the other is connected to a wire 26 which leads to a suitable 10 source of current (not shown).

The wire 12 leads from the signal arm through the lower tubular bolt 4, while the wire 26 extends down the side of the post to inside the car. When the signal is in a neutral position the upper contact 25 engages the shaft between the band so that the circuit is then broken; the knob 23 being then in a vertical position. On turning said knob to the right or left from such position the signal arm will be correspondingly raised or lowered and the upper contact strip will then engage the metal band on one side or the other of the break, closing the circuit and causing the bulb to be illuminated.

25 The shaft and band are notched at the spaced points thereon where the contact strips engage the same at the respective positions of the signal, while the strips 25 are provided with small protuberances as shown, 30 which fit into the recesses.

These strips are of fairly stiff metal so that this arrangement causes the shaft and parts connected thereto to remain set at any position to which they may be moved, unless 35 intentionally turned from such positions by manipulation of the knob 23.

The glass tube is preferably colored red inside so as to show red when the bulb is lit, but is colored white on the outside so as to 40 give a dull appearance when the light is extinguished and the signal is "dead" or in a neutral position. The tubular bolts not only provide a convenient means for rigidly connecting the parts of the structure together in 45 proper relationship, but also serve as conduits for the necessary operating and current wires, thus maintaining a neat appearing structure, as will be evident.

From the foregoing description it will be 50 readily seen that I have produced such a device as substantially fulfills the objects of the invention as set forth herein.

While this specification sets forth in detail the present and preferred construction of the 55 device, still in practice such deviations from such detail may be resorted to as do not form a departure from the spirit of the invention, as defined by the appended claim.

Having thus described my invention what 60 I claim as new and useful and desire to secure by Letters Patent is:

A direction signal structure for a motor vehicle comprising a signal member having a horizontal pivot to extend lengthwise of the 65 vehicle, a support for said pivot adapted for

attachment on the outside of a vertical body post of the vehicle, a relatively short arm projecting upwardly from the signal adjacent its pivot, another similar arm disposed inwardly of the post in transverse alignment with the signal arm, a fixed pivot for the lower end of said other arm parallel to and on a level with the signal pivot, a link connecting the upper ends of the arms, and hand means applied to the pivot of the inner arm 75 to turn said arm.

In testimony whereof I affix my signature.
JOHN P. WILLIAMS.
